UNITED STATES PATENT OFFICE.

CHARLES S. BIRD, OF WALPOLE, MASSACHUSETTS.

COVER BOARD FOR SHINGLE BUNDLES AND THE LIKE.

Application filed September 7, 1921. Serial No. 499,037.

To all whom it may concern:

Be it known that I, CHARLES S. BIRD, a citizen of the United States, residing at Walpole, in the county of Norfolk and State of Massachusetts, have invented certain new and useful Improvements in Cover Boards for Shingle Bundles and the like, of which the following is a specification.

This invention has reference to means for bundling shingles and is adapted, more particularly, for use in connection with paper or felt shingles, which by reason of their nature cannot be readily packed or bundled as can the ordinary wooden shingle.

15 The main object of the present invention is to provide cover boards formed of fiber board and the like, and to so protect the edges thereof as to preclude the wires, commonly employed for securing the bundle, 20 from cutting through the edges of the board and thus injuring the shingles.

The boards, of which there are two for each bundle, are alike in form and the body thereof is preferably formed from a sheet 25 of fiber board folded upon itself and provided with edge reinforcing means, as hereinafter set forth.

The invention is illustrated in the annexed drawings, wherein,—

30 Fig. 1 is a perspective view of a bundle of shingles with the improved cover boards thereon; and

Fig. 2 a perspective view of a portion of one of the boards with parts broken away 35 to more clearly disclose the construction.

The board is formed from a piece of fiber board and comprises a body section 1, of a width preferably slightly greater than the length of the shingle, and of a length corresponding to the width of the shingle, and 40 two inturned flaps 2 and 3. Secured to the edges of the board thus produced, is a strengthening strip 4, formed preferably of

tough paper, though cloth or other material may be employed, said strip being pasted 45 to the board. During the process of placing the strip a cord 5 is laid against each edge of the board within the fold of the strip 4, the strip serving to position and hold the cord directly against the edge of the board 50 and to prevent its displacement. Not only is it held by the strip but the adhesive employed to secure the strip likewise serves to secure it in place. If desired the cord itself may be treated with adhesive.

55 While cords are found all sufficient when held in place as above described, to prevent the cutting through of the binding wires, one might employ wires in lieu of the cords, though the wire is more expensive and not 60 so ready of placement. The term strand as employed in the following claims is to be understood as covering either the wire or cord.

What is claimed is,—

65 1. A binder board for shingle bundles and the like, formed of a sheet of fiber board with two of the opposite marginal sections of the board infolded upon the body of the board; a strand extending along each edge 70 produced by the folds; and a folded strip embracing each of the strands and secured to the board.

2. A binder board for shingle bundles and the like, formed of a sheet of fiber board 75 with two of the opposite marginal sections of the board infolded upon the body of the board; a cord extending along each edge produced by the folds; and a folded strip of paper embracing each of the cords in its fold 80 and holding said cord against displacement, said strips being pasted to the body of the board and the infolded sections.

In testimony whereof I have signed my name to this specification.

CHARLES S. BIRD.
